United States Patent

Des. 240,735
Patented July 27, 1976

240,735

ELECTRONIC CALCULATOR

Shiro Anzai, Yamato, and Kunio Hirose, Tokyo, Japan,
assignors to Canon K.K., Tokyo, Japan

Filed Aug. 5, 1974, Ser. No. 494,915

Term of patent 14 years

Int. Cl. D18—01

U.S. Cl. D26—5 C

FIG. 1

FIG. 2

FIG. 3

FIG. 4

FIG. 5

FIG. 1 is a front perspective view of an electronic calculator embodying our new design;

FIG. 2 is a top plan view thereof;

FIG. 3 is a side elevational view thereof;

FIG. 4 is a rear elevational view thereof; and

FIG. 5 is a bottom plan view thereof.

The indicia shown in broken lines in FIGS. 1 and 2 is for illustrating purposes only and forms no part of the claimed design.

We claim:

The ornamental design for an electronic calculator, as shown and described.
